(57) **CLAIM**

I claim the ornamental design for an endless track of an off-road vehicle, as shown and described.

DESCRIPTION

FIG. 1 is a perspective view of an endless track of an off-road vehicle according to the present design, it is understood that a segment of the tread pattern is repeated over the length of the track shown by the broken lines in FIG. 6.

FIG. 2 is a top view of the endless track of an off-road vehicle of FIG. 1.

FIG. 3 is a first elevational view of the endless track of an off-road vehicle of FIG. 1 showing the segment of the tread pattern when seen in the direction illustrated by line 3-3 on FIG. 2. Although the segments of the tread pattern are offset as viewed horizontally in the figure, the left portion and the right portion of the tread are shown in a single figure for clarity of illustration.

FIG. 4 is a second elevational view of the endless track of an off-road vehicle of FIG. 1 showing the tread pattern when seen in the direction illustrated by line 4-4 on FIG. 2. Although the segments of the tread pattern are offset as viewed horizontally in the figure, the left portion and the right portion of the tread are shown in a single figure for clarity of illustration.

FIG. 5 is a side elevational view of the endless track of an off-road vehicle of FIG. 1 showing the segment of the tread pattern when seen in the direction illustrated by lines 5-5 on FIG. 2; and,

FIG. 6 is a perspective view of the endless track of an off-road vehicle shown with the endless nature of the track shown by the broken lines.

The broken lines form no part of the design and are for illustrative purposes only.
